Primary Examiner — Abraham Bahta(74) *Attorney, Agent, or Firm* — Fennemore Craig, P.C.(57) **CLAIM**

The ornamental design for a bag, as shown and described.

DESCRIPTION

FIG. 1 is a top front perspective view of a first embodiment of the bag showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side view thereof;

FIG. 7 is a left side view thereof;

FIG. 8 is a top perspective view of the second embodiment of the bag;

FIG. 9 is a front elevation view thereof;

FIG. 10 is a rear elevation view thereof;

FIG. 11 is a top plan view thereof;

FIG. 12 is a bottom plan view thereof;

FIG. 13 is a right side view thereof; and,

FIG. 14 is a left side view thereof.

The portions shown in broken lines are for illustrative purposes only and form no part of the claimed design.

1 Claim, 10 Drawing Sheets(56)
